DESIGN FOR A BOTTLE

Hugh Genske, Philadelphia, Pa.

Application October 22, 1945, Serial No. 123,094

Term of patent 7 years

(Cl. D58—8)

To all whom it may concern:

Be it known that I, Hugh Genske, a citizen of the United States, residing at Philadelphia, in the county of Philadelphia and State of Pennsylvania, have invented a new, original, and ornamental Design for a Bottle, of which the following is a specification, reference being had to the accompanying drawing, forming part thereof.

In the drawing:

I claim:

The ornamental design for a bottle, as shown.

HUGH GENSKA.
